F. J. Richards.

UNITED STATES PATENT OFFICE.

JOSEPH GANGI, OF NEW YORK, N. Y.

WATER-WAVE DEVICE FOR HAIR.

Application filed October 8, 1923. Serial No. 667,227.

To all whom it may concern:

Be it known that I, JOSEPH GANGI, a citizen of the United States, residing in New York, in the county of New York and State of New York, have invented certain new and useful Improvements in Water-Wave Devices for Hair, of which the following is a specification.

The present invention relates to devices for providing what is commonly termed a water wave in women's hair, and to the method of producing the wave, and one object of the invention is to provide a device of this character, which shall be small and compact in size, simple in construction and easily employed.

Another object is to provide a device in which an ordinary small comb, such as is customarily used in women's hair toilet, is employed and with which a clamping means cooperates to form the wave.

I accomplish these objects, and such other objects as may later appear herein, by the invention, one preferred form and two modifications of which are described, by way of example, in the subjoined specification and shown in the accompanying drawing, in which—

Figure 1 is a top view of the preferred form;

Fig. 2 is a sectional view on the line 2—2 of Fig. 1, looking in the direction of the arrows;

Fig. 3 is a diagrammatic view;

Fig. 4 is a side view of one modification of the device;

Fig. 5 is a rear view of Fig. 4;

Fig. 6 is a fragmentary view of Fig. 4, the comb being removed, and

Fig. 7 is a side view of a second modification.

Similar reference characters denote similar parts throughout the several views.

Referring to Fig. 1, the device is made of suitable metal and comprises the spring clip generally denoted by 10 which is secured to the comb 11, the pivotally movable clamping member generally denoted by 12, and the pressure member generally denoted by 13.

The spring clip 10 comprises the resilient opposed plates 14 and 15 connected by the portion 16 so that these plates cooperate to form a clasp, the plate 14 having a plane face and the plate 15 having an indentation 17 in its face intended to engage in

an ornamental longitudinal indentation or groove usually formed at the back of combs near the rear edge thereof, whereby when the back of the comb is inserted between the faces 14 and 15, the comb will be clasped by the spring clip and removably secured thereto, and is slidable on the back edge of the comb, this slidable feature permitting adjustment of the device longitudinally of the comb relative to the hair engaged by the teeth of the comb. Or if the comb has no such indentation but has a plane surface at its back, both the opposed faces of the plates 14 and 15 may be made plane and the spring clip may be fixedly secured thereto by suitable pins or rivets, not shown but readily understood, passing through the plates 14 and 15 and through the comb. The connecting portion 16 is provided with the opposed apertured ears 18.

The clamping member 12 comprises the head or block 19 having a hole transversely therethrough, and the arm 20. The block 19 is arranged to engage or fit between the ears 18 and is pivotally secured thereto by the bolt 21 passing through the hole of the block and through the ears 18, the under and rear end portions 22 and 23, shown clearly in Fig. 3, being straight, and intersecting at a right angle, for the purpose later stated.

The arm 20 extends upwardly and is provided for a portion of its length with a decided curve 24 for the purpose later stated. The arm 20 has transversely secured to the outer end thereof the clamping plate 25.

The pressure member 13 is of resilient or spring material and has a straight portion 26 which is secured, as by the rivet 27 to the outer face of the plate 14, and has an upstanding portion 28 which is engageable with the straight rear portion 22 of the block 19, which forms a right-angle with the portion 21 of the block, for exerting pressure on the block and tending to force the arm 20 and clamping plate 25 downwardly, the free end of the portion 28 being turned outwardly as at 29 for providing means for manipulating the pressure member.

The use of the device in forming the wave by my method is as follows:

The operator first combs and wets the hair, the hair is then separated into strands, and is folded to form a loop as shown at A, Fig. 3, the teeth of the comb are passed

through the strand at the base of the loop A, the arm 12 is then snapped down over the loop A so that the clamping plate 25 engages the base of the loop A at a point opposite to the point of insertion of the teeth of the comb with the strand of hair between said member and the comb as shown at B, the loop freely occupying the space beneath the curved portion 24 of the arm 20 and 5 without interference therefrom, the device being left in clamping position for the desired length of time, a plurality of the devices being used, the devices being in series in alignment and a plurality of parallel 10 series being employed. The devices later are removed by releasing the clamping members and a so-called water wave is provided.

Referring to Figs. 4, 5 and 6, the spring clip 30 is similar to the spring clip 10. The 20 support 31 is secured at its lower end to the connecting end portion of the spring clip 30 and has at its upper end the apertured ears 32, between which the block 33 of the straight portion of the arm 34 is pivotally 25 secured, the arm having on its curved end the clamping member 35. The pressure member 36 is pivotally secured at its lower end to the spring clip 30 and at its upper end bears against the rear side of the block 33 and tends to force the arm 34 and its 30 clamping member 35 downwardly, the pressure member being provided with the manipulating end 37.

Referring to Fig. 7, the spring clip 38 and 35 support 39 are the same as in Fig. 4. The cylindrical case 40 has a downwardly extending lug 41 which is pivotally secured between the ears 42 of the support 39 and has a chamber 43 open at one end and closed 40 at the other end except for the bore or hole 44. The arm 45 has a straight end portion 46 and a curved end portion 47, the straight portion having a head 48 thereon, the straight end portion 46 extending through 45 the hole 44 back of the straight portion and said head being located in said chamber. A spring 49 is arranged around the straight portion 46 and secured at one end to the wall of the chamber 43 and bearing at its 50 other end against the head 48 with tendency to force this head towards the open end of the chamber. The straight portion 46 outwardly of and adjacent to the closed end of said chamber has a thread thereon with 55 which the nut 50 cooperates so that by pushing forwardly the nut the reach of the arm 45 may be increased as shown in outline for positioning the end of the arm over the fold of the hair as at B, Fig. 3. The pressure 60 member 51 is pivotally secured at its lower end to the connecting end portion of the spring clip 38, and at its upper end bears against the open end of the case 43 with tendency to force the arm 45 and clamping 65 plate 52 downwardly, the pressure member

having on its upper end the manipulating knob 53.

Having thus described my invention, it should be understood that there may be modifications thereof and variations therein without departing from the spirit of the invention or exceeding the scope of the appended claims.

What I claim and desire to protect by Letters Patent is:

1. A hair wave providing device comprising a hair comb, pivotally movable means removably attached to the hair comb, and having an end member engageable with the teeth of the comb transversely of the teeth 80 for clamping the hair on the teeth, and having an upwardly extending portion between the point of pivotal attachment of said means to said comb and said end member for providing a loose loop of hair between 85 said point of pivotal attachment and the point of engagement of said member with the hair.

2. A hair wave providing device comprising a hair comb; and pivotally movable 90 means removably attachable to the hair comb having an end member engageable with the teeth of the comb transversely of the teeth and spring pressed thereon for clamping the hair on the teeth and providing a loose loop of the hair between the point of attachment of said means to the comb and the point of engagement of said member with the hair.

3. In a device for providing a water hair wave, the combination of, a hair comb; and means removably secured to the comb and slidably movable thereon; said means comprising an arm having a curved portion with 100 a plate at the end thereof engageable with the teeth of the comb transversely of the teeth and pressed thereupon.

4. In a device for providing a water hair wave, the combination of, a hair comb; a spring clip engageable with the comb; an 110 arm pivotally secured at one end to the spring clip and having a clamping plate secured to the opposite end and engageable with the teeth of the comb transversely of the teeth; and a pressure member cooperating with the arm for pressing said plate upon the teeth of the comb.

5. In a device for providing a water hair wave, the combination of, a hair comb; a spring clip engageable with the comb; an 120 arm pivotally secured at one end to the spring clip and having a curved portion provided at its end with a clamping plate engageable with the teeth of the comb transversely of the teeth; and a pressure member cooperating with the arm for pressing said plate upon the teeth of the comb.

6. In a device for providing a water hair wave, the combination of, a hair comb; a spring clip engageable with the comb and 130

slidably movable thereon; an arm pivotally secured at one end to the spring clip and having a curved portion provided at its end with a clamping plate engageable with the 5 teeth of the comb transversely of the teeth; a pressure member cooperating with the arm for pressing said plate upon the teeth of the comb; and means for operating the pressure member.

10 7. In a device for providing a water hair wave, the combination with a hair comb, of pivotally movable means removably attached to and slidable thereon, said means comprising an arm having a curved portion with a plate at the end thereof engageable with the teeth of the comb, transversely of the teeth and pressed thereupon. 15
